COMBINED RADIO AND PENHOLDER

Samuel Frankel, 236 5th Ave., New York, N.Y.

Filed Jan. 21, 1960, Ser. No. 59,133

Term of patent 14 years

(Cl. D56—4)

FIG. 1

Fig. 1 is a perspective view of a combined radio and penholder, showing my new design; and

Fig. 2 is a side elevational view thereof.

The back of the article is substantially plain and unornamented.

I claim:

The ornamental design for a combined radio and penholder, as shown and described.
